(57) CLAIM

The ornamental design for a football field table top, as shown and described.

DESCRIPTION

FIG. 1 is a perspective view of the football field table top;
FIG. 2 is a front view of the table top;
FIG. 3 is a right side view of the table top;
FIG. 4 is a top view;
FIG. 5 is a rear view;
FIG. 6 is a left side view; and,
FIG. 7 is a bottom view.

The broken lines showing the table legs are for environmental purposes only and form no part of the claimed design.
